LINE GUIDING DEVICE

Albert Kannegister, Little Rock, Iowa

Application March 30, 1938, Serial No. 199,054

1. Claim. (Cl. 242—157)

This invention relates to line guiding devices, and more particularly to an improved line guiding means adapted for use with binders or the like.

5 An object of this invention is to provide an improved line guide in the form of an attachment which may be readily and quickly applied to the present parts of a binder and which is so constructed that the friction of the line passing 10 through the guide will not form a groove therein.

Another object of this invention is to provide a line guide which may be constructed from glass or the like and which includes a novel attaching means whereby the guide may be readily and 15 quickly attached to the present parts of a binder without disturbing the body parts.

A further object of this invention is to provide an improved line guiding means for the needle of a binder wherein the line is supported partly on 20 rotatable glass guiding rollers and partly on stationary glass eyes so that the passage of the line through the stationary eye and the rotatable guide members will not cause grooves to be formed therein as is at present the case.

25 Still another object of this invention is to provide a line guiding eye which is formed of glass or the like and which includes a novel clamping means which not only detachably holds the eye or guiding member therein, but also holds the glass eye or guiding member on the present parts of the binder structure.

To the foregoing objects and others which may hereinafter appear, the invention consists of the novel construction, combination and arrangement of parts as will be more specifically described and as illustrated in the accompanying drawing, wherein is shown embodiments of the invention, but it is to be understood that changes, variations and modifications may be resorted to 40 which fall within the scope of the invention as claimed.

In the drawing:

Figure 1 is a fragmentary perspective view of 45 a binder needle having a line guiding means constructed according to an embodiment of this invention mounted thereon,

Figure 2 is a detail side elevation of the improved guiding eye detachably secured to the conventional guide eye at present forming a part of 50 the binder structure,

Figure 3 is a sectional view partly in elevation taken on the line 3—3 of Figure 2,

55 Figure 4 is a perspective view of the holder or clamping device for the improved guide,

Figure 5 is a plan view of the support shown in Figure 4 in blank form,

Figure 6 is a sectional view similar to Figure 3 of a modified form of this guide eye, and

Figure 7 is a vertical section of a guide roller 5 constructed according to an embodiment of this invention.

Referring to the drawing, the numeral 10 designates generally a needle at present forming part of a binder structure which is secured to an operating shaft 11. The needle 10 comprises a radial arm 12 and an arcuate member 13 secured to the outer end thereof which is pointed at one end and this needle is adapted to be rocked in a conventional manner by rocking or rotation of the operating shaft 11.

A guide member is secured to the radial arm 12 adjacent the inner end thereof and comprises an arm 15 having an eye or annulus 16 secured to the outer end thereof. This arm 15 is secured to the radial arm 12 by means of a rivet or fastening member 17. The structure hereinbefore described is at present conventional structure in a binder and a binder twine or cord 18 is adapted to be passed through the eye 16 and is then guided over rollers 19 to the pointed end of the needle 13. The eye 16 at present is formed of metal and the friction caused by the passage of the twine 18 therethrough forms a groove or channel on the inside of the eye so that when knots or enlarged portions in the twine 18 pass through the eye 16 these knots or enlarged portions tend to cause breakage of the twine or in other ways tend to retard the free movement of the twine or cord 18 through the end of the needle. 25

In order to provide a means in combination with the eye 16 whereby the twine 18 may freely pass therethrough, I have provided an annulus generally designated as 20 which is disposed concentrically of the eye 16. This annulus 20 comprises a glass sleeve 21 which is provided with rounded opposite end portions 22 in the bore thereof and which is also provided with a rib or bead 23 at its outer end. The sleeve 21 is provided at its inner end with a seat 24 adapted to 30 engage the rounded surface of the eye 16 so that the sleeve 21 may snugly rest on this eye 16 and be held concentrically thereof. 35

The guiding member 20 is detachably clamped on the eye or annular member 16 by a clamping device generally designated as 25. This clamping member 25 comprises an annular base member 26 provided with a plurality of upstanding clips or arms 27 which are adapted to engage about the rib 23 as shown in Figure 2. The clips 40 45 50 55

27 are struck from the annular member 26 on the inside thereof and are then bent outwardly at substantially right angles, being formed adjacent their outer ends with curved portions 28 which 5 are adapted to engage about the bead 23. A plurality of circumferentially spaced apart clips or clamping members 29 are struck from the blank of which the clamping member 25 is formed and have a configuration substantially coincident with 10 the configuration of the eye 16. Initially as shown in Figure 5 these clamping clips 29 are straight and are then bent in substantially the configuration shown in Figure 4. The base member 26 is adapted to engage one side of the eye 16 so as to 15 support the guiding member 20 and the clips 29 firmly hold the base 26 in concentric position on the eye 16.

In Figure 6 there is disclosed a modified form 20 of guide member wherein a sleeve 21' is provided which is adapted to engage within and extend through the guide eye 16'. The sleeve 21' is provided with a bead 23' at one end and a clamping member 25' similar to the clamping member 25 disclosed in Figure 4 is secured to the guiding member 20' so as to detachably hold the guide member 20' on the guide eye 16'. In this instance, the ends 30' of the attaching clips engage below the eye 16 and may project inwardly a sufficient degree to contact with the adjacent end 30 of the sleeve 21'.

In Figure 7 there is disclosed a glass roller 31 provided with a peripheral groove 32 and this roller 31 is provided in the bore thereof with a metal sleeve 33 which has the opposite ends thereof outturned so as to provide flanges 34. In this manner the flanges 34 act as protecting means and as spacing means for spacing the adjacent ends of the roller 31 from the needle 13 and also from the head of a securing member 35. In the present instance, the securing member 35 is disclosed as a screw, but it will be understood that this member 35 may also be in the form of a headed rivet or the like. The provision of a metal sleeve or bushing 33 on the inside of the roller 31 provides a wear surface for the roller 40

31 so that the roller 31 will not cut into the surface of the bolt or rivet 35.

In the use of this line guiding means the rollers at present in use on the needle 13 may be removed and the glass rollers 31 substituted therefor. The conventional guide member 16 with the support 15 may be retained on the radial arm 12 and the clips 29 engaged over the outside of the eye 16 so as to firmly hold the guide member 20 concentrically of the old guide eye 16. Preferably, the bore of the guide member 20 is relatively smaller than the bore of the eye 16 so that the twine 18 will not have a tendency to contact with the surface of the guide member 16 in the movement of the twine through the eye or guide member 20. 10 15

This line guiding attachment is so constructed that it can be easily and quickly mounted on the present guide 16 of the binder without changing or in any way disturbing the present construction 20 of this guide member 16. Through the use of glass or similar substance, the guide 20 will not have a groove formed therein caused by friction of the line passing therethrough as is the case where a metal guide eye is used. This guide attachment will therefore provide a guiding means for the twine which will have a life substantially equal to the binder, thus making it unnecessary to stop the operation of the binder due to the breaking of the twine as it passes through the 30 eye which may be formed with a groove therein due to the friction of the line in the eye. 25

What I claim is:

A line guide comprising an annulus, a ring-shaped base member, circumferentially spaced apart resilient clips carried by and disposed substantially at right angles to the inside periphery of said base member engaging said annulus to hold said annulus on said base member, and circumferentially spaced apart resilient clips carried by and disposed substantially at right angles to the outer periphery of said base member and extending oppositely with respect to said first clips to detachably hold said base member on a support. 35 40 45
